TRACING HANGER

Loell L. Hyler, Peoria, Ill., assignor to R. G. Le Tourneau, Inc., Stockton, Calif., a corporation

Application April 21, 1942, Serial No. 439,853

2 Claims. (Cl. 24—154)

This invention relates in general to an improved cabinet for the reception of tracings, drawings, prints, and other sheets which must be maintained in non-folded condition for subsequent use; and in particular the invention is directed to, and it is the principal object to provide, a sheet hanger arranged to receive and suspend a relatively large number of sheets within a minimum of space and in position for ready access to each.

A further object of the invention is to provide a sheet hanger which includes, in a suitable housing or cabinet, a unique assembly of supporting wires mounted in the cabinet, and wire engaging clips attached to the sheet and releasably suspended from said wires.

An additional object of the invention is to provide a sheet hanger, as above, wherein the suspending clips are arranged so that they remain on the sheet when the latter is removed from the cabinet, and can pass through an automatic blue printing machine, for example, without damage to either the clip or the machine.

It is also an object of the invention to provide novel connector units between the ends of the horizontal supporting wires and the sides of the cabinet; said units being adjustable to properly tension said wires.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Figure 1 is a front elevation of the sheet hanger as in use; the front curtain or drape being shown partially open.

Figure 2 is an enlarged fragmentary transverse section on line 2—2 of Fig. 1.

Figure 3 is an enlarged fragmentary sectional elevation of one of the wire end connector units.

Figure 4 is an enlarged fragmentary elevation of one of the suspending clips as attached to a sheet.

Referring now more particularly to the characters of reference on the drawing, the improved sheet hanger is housed within an upstanding rectangular cabinet which includes side panels 1, a back panel 2, and a top 3; the front of the cabinet initially being open and provided with a flexible drape or slide curtain 4 suspended for sliding

movement along a horizontal wire 5 mounted in the cabinet adjacent the top and front thereof. The cabinet is preferably of knock-down type so that it may be readily dismantled for movement from place to place if necessary.

Within the cabinet immediately below but spaced from the top 3, there are two pairs of horizontal wires 6, one pair being adjacent the front of the cabinet while the other pair is adjacent the back of the cabinet; the wires of each pair being parallel and spaced apart laterally relative to each other, and the corresponding wires of the separate pairs being spaced an equal distance, as clearly shown in Fig. 2. All of the wires are in the same horizontal plane, and at their ends are connected with the side panels 1 of the cabinet by means of tensioning units, indicated generally at 7, each of which is constructed as follows:

The wires 6 at their ends pass through ports 8 in the side panels 1 into an enclosure or chamber 9 formed by a cap 10 fixed on the exterior of the side panel 1 in surrounding relation to port 8. The outer end of cap 10 is formed with a central opening 11 through which a cap screw 12 projects, the head 13 of said cap screw being in chamber 9. The cap screw is formed with a longitudinal and central bore 13 through which the corresponding wire 6 is threaded from the head end of the cap screw to the other end, where said wire is looped as at 15 and then threaded back through the cap screw and bent laterally, as at 16. A nut 17 is threaded on the cap screw exteriorly of the cap 10 and abuts the outer end thereof. With tightening of the nut 17, the corresponding wire 6 is placed under tension. To prevent loop 15 from pulling through bore 13, a transverse pin P may be disposed in the loop.

The sheets of tracings 18 or the like are suspended in the cabinet in face to face relation and facing the side panels 1. In other words, one side edge of the sheets 18 is presented adjacent the front of the cabinet, while the other or opposite side edge is disposed adjacent the back panel 2.

The sheets 18 are individually suspended from the wires 6 by means of a pair of suspending units indicated generally at 19 secured to and spaced along the upper edge of said sheets; such units cooperating with corresponding ones of the pairs of said wires. In order to permit of the hanging of a maximum number of sheets, without interference by the suspending units 19, the latter are mounted on alternate sheets so as to cooperate alternately with the different wires of said separate pairs. It will thus be seen that the

suspending units on one sheet are offset relative to the suspending units on the adjacent sheets and consequently said units do not abut each other and the sheets occupy materially less space along the suspending wires.

Each of the suspending units 19 comprises an elongated, horizontally disposed eye 20 which is disposed above but substantially abuts and extends along the upper edge 21 of the sheet 18. A length of adhesive tape 22 is looped through the eye and is adhered to the adjacent portion of the sheet 18 on opposite sides thereof. To further assure against separation of the adhesive tape 22 from sheet 18, metal staples 23 may be projected through the adhesive tape and the portion of the sheet therebetween.

A hook 24 extends upwardly from the eye 20 substantially centrally of the ends of the latter and engages over the corresponding wire 6; such hook at its outer or free end being formed as an elongated leg 25 which extends at a downward and outward slope to a termination short of but adjacent the upper edge of eye 20. The space 26 between the lower end of leg portion 25 and eye 20 is less than the diameter of wire 6, so that the suspending units are placed on or removed from the wires with a snap action, which is possible due to the resiliency of the leg portion 25 relative to the remainder of the hook.

In order to place a sheet in the cabinet, or to remove a sheet, the front curtain 4 is opened to the necessary extent and the two suspending units 19 are either engaged with or detached from the proper ones of the wires 6.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

10 1. A sheet hanging unit adapted to be secured in plurality and in spaced relation along the upper edge of a sheet so as to suspend the latter from a horizontal wire or the like; said unit comprising a horizontally elongated eye disposed above and extending along the upper edge of the sheet with the lower run of the eye adjacent said edge, means connected between said lower run of the eye and the sheet, securing the eye to the same, a wire engaging hook upstanding from the upper run of said eye intermediate the ends of the latter, said hook being vertically elongated and the free leg thereof being extended downwardly to a point closely adjacent but short of said upper run of the eye; such extended leg being resilient in relation to the eye, and the space between the lower end of said resilient leg and said upper run of the eye being less than the diameter of the supporting wire.

2. A sheet hanging unit as in claim 1 in which said extended leg of the vertically elongated hook extends at a downward and outward slope, the lower end of said extended leg terminating at a point, lengthwise of said elongated eye, adjacent but short of one end of said eye.
